UNITED STATES PATENT OFFICE.

ROY J. BUELL, OF DETROIT, MICHIGAN.

ATTACHMENT FOR BATH-TUBS.

1,235,652.

Specification of Letters Patent. Patented Aug. 7, 1917.

Application filed December 8, 1915. Serial No. 65,857.

To all whom it may concern:

Be it known that I, ROY J. BUELL, a citizen of the United States, residing at Detroit, county of Wayne, State of Michigan, have invented a certain new and useful Improvement in Attachments for Bath-Tubs, and declare the following to be a full, clear, and exact description of the same, such as will enable others skilled in the art 10 to which it pertains to make and use the same, reference being had to the accompanying drawings, which form a part of this specification.

This invention relates to attachments for 15 bath-tubs and its object is a device combining in a single unit attachable to the tub, a water-tank, a heater therefor, a fuel supply tank and a pump for withdrawing the water from the tub. The tank is provided 20 with an outlet leading into the tub and a fixture is provided connecting the outlet of the tub and the pump attached to the water tank. Another object of the invention is 25 a heater so arranged that the water as it becomes heated is delivered adjacent to the outlet of the tank so that on opening the said outlet to allow the water to flow into the tub the first water drawn is the warmest water and continues to flow principally from 30 the tank through the heater until the tank is empty. A further object is a combined tank and heating appliance that may be readily attached or detached from the tub and when attached is movable with the tub being entirely supported thereby. These and other 35 objects and the several novel features of construction are hereinafter more fully described and claimed and shown in the accompanying drawings in which—

40 Figure 1 is a vertical section of a water heating unit embodying my invention supported on a bath tub.

Fig. 2 is a section taken on line $\alpha-\alpha$ of Fig. 1.

45 Fig. 3 is a plan view of the water tank and attached instrumentalities.

Fig. 4 is a detail in perspective of the discharge fitting to which the pump is attached.

50 Similar characters refer to similar parts throughout the drawing and specification.

The tub 1, preferably of metal and of any approved form, is provided with the usual rim 2 and waste outlet 3. The tub is preferably portable as shown, being supported

in a framework 4 mounted on rollers 5, and the particular utility of the combined tub and water heating device is its adaptability for use in towns and villages and other places in which no common water supply 60 system is provided. With my device a simple, inexpensive and efficient apparatus is provided for heating water for bathing purposes and for readily removing used water from the tub. 65

In the embodiment of the invention here shown a tank 6 for water is provided having a cover 7 at the top and, as shown in Figs. 2 and 3, the tank is provided with brackets 8, 8 attached thereto and adapted to rest on 70 the rim 2 of the tub. As is also shown in Fig. 2, the water tank is narrower at the top than at the bottom, the large portion thereof fitting beneath the rim 2 of the tub and the bracket so spaced from such enlarged portion that the shoulder of the tank is held tightly against the rim with the vertical wall 9 thereof closely engaging the wall 10 of the tub. The walls 9 and 10 are similarly apertured to receive a standard valved 80 fitting 11, the inner threaded end of which extends into the tank and secured in any approved manner. By means of the fitting 11 the water in the tank may be discharged into the tub. 85

As may be seen particularly in Fig. 1, a fuel tank 13 is provided, attached to one side of the water tank, and having a plugged inlet 14 through which the tank may be filled and by means of which said tank is 90 made air tight. Connecting to the upper end of the tank 13 is a tube 15 having a bulb 17 on the lower end thereof by means of which air may be forced into the tank to produce a pressure on the fuel to insure a proper feeding thereof to the burners located beneath the water tank and connecting with the fuel tank by means of a pipe line 18. The preferable fuel, is gasolene, 95 and the burners are shown somewhat diagrammatically but are of the ordinary well known type for burning kerosene or gasolene. The burners are shielded by a depending apron or flange 19 as shown more particularly in Fig. 2.

The bottom of the water tank 6 is provided with recesses or pockets 20 and 21, one above each burner 17, into which the flame and heat from each burner respectively rises. In these pockets in each instance is a 110

pipe 22 arranged in a cone shaped coil so that each turn of the pipe is exposed to the flame and heat from the burner. One end of the pipe passes through the wall of the pocket at 23 opening into the lower part of the water tank and the upper end of the pipe passes through the opposite wall of the pocket at 24 discharging preferably into a pocket 25 surrounding the outlet plug 11 which extends across the tank to receive the piping from both the pockets as is indicated in Fig. 1. The upper horizontal wall of the pocket 25 is apertured at 26 preferably in several places and the vertical wall is provided with an aperture or apertures 26^a at the bottom of the tank through which it may be drained.

The purpose of the pocket 25 primarily is to provide a means of segregating the heated water from the colder water of the tank so that on opening the fitting 11 to allow the water to flow from the tank the first water drawn is the hottest water and the purpose of the apertures 26 is to enable the entire contents of the tank to become heated when the valve 11 is closed. The heated water from the coil flows into the pocket 25 upward through the apertures 26 and the colder water enters the coil through the inlet 23. As the pocket 25 incloses the outlet it is necessary to provide the drainage apertures 26^a.

Connected with the waste outlet 3 of the tub is a one piece fitting 27 shown clearly in Figs. 1, 2 and 4. The fitting has an end 28 threaded to receive the threaded portion of the apertured outlet plug of the tub and also has an elongated portion terminating in an upturned internally threaded end 29 to receive the threaded end of the pump cylinder 30 as shown in Fig. 1. The pump may be of any approved type adapted for the purpose preferably one having a piston 31 provided with a ball valve 32 and the lower end of the pump cylinder is provided with a ball check valve 33 opening on upward movement of the pump piston and closing on the downward stroke during which the ball and valve 32 of the piston opens allowing the water to flow through the piston to the upper side thereof in the usual well known manner. The upper end of the pump cylinder is provided with an outlet spout 34, and an operating rod 35 is attached to the piston provided at the upper end with a handle by means of which it may be operated. The pump cylinder stands vertically at the side of the water tank and may be secured in position by any approved means as a strap 36 passing about the pump cylinder and secured to the wall of the tank.

The fitting 27 is provided with a downwardly extending portion 38 having an internally threaded end to receive a plug 39. 65 The portion 38 of the fitting is also provided

with an internally threaded aperture 40 adapted to receive a drain valve 41 as indicated in Fig. 2. The tank may thus be emptied by means of the pump or the drain valve 41 as may be desired, and by providing the fitting with the plug 39 the said plug may be removed and a drain pipe attached in place thereof whenever the tub is set in permanent position.

By my improved water heating device, the several elements of which are united to provide a single unit attachable to the tub, a bath tub of ordinary form may be utilized without involving particular expense by simply mounting the device upon the end thereof as described. An inexpensive bathing apparatus is thus provided particularly adapted for use in isolated districts and enabling persons in such districts to avail themselves of sanitary appliances equivalent to those in use in the larger towns and cities.

Having thus described my invention, what I claim and desire to secure by Letters Patent of the United States is—

1. An apparatus for use in conjunction with a bath-tub comprising in a single unit adapted to be solely supported by the tub, a water tank, a heating apparatus therefor, a fuel supply tank for the heating apparatus, a pump carried by the tank, a pipe fitting secured to the pump and adapted to be connected with the waste outlet of the tub, and means for supporting the tank on the tub.

2. An apparatus for use in conjunction with a bath tub comprising in a single detachable unit adapted to be solely supported by the tub, a water tank, a heating apparatus therefor, a fuel supply tank for the heating apparatus, a pump carried by the tank, a pipe fitting secured to the pump adapted to be connected with the waste outlet of the tub, brackets adapted to support the tank and connected parts on the tub, and a valved fitting providing an outlet for the tank discharging into the tub.

3. A water heating apparatus for use in conjunction with a bath tub comprising in combination with a tank adapted to be supported by the tub and having a valved discharge outlet leading thereinto, of a fuel burner, the tank being provided with a pocket above the burner, a pipe in the pocket connecting with the tank at the bottom and discharging thereinto adjacent said outlet.

4. A water heating apparatus for use in conjunction with a bath tub comprising in combination with the tank adapted to be secured to the tub and having a valved discharge opening leading thereinto, of a fuel burner, a pocket or recess formed in the bottom of the tank above the burner, a second pocket adjacent the first named pocket and inclosing the valved opening, a coiled pipe in the first named pocket connecting

with the tank at the bottom and discharging into the second named pocket.

5. A water heating apparatus for use in conjunction with a bath tub comprising in combination with a tank adapted to be secured to the tub and having a valved discharge opening leading thereinto, a fuel burner, a pocket or recess formed in the tank above the burner, a second pocket adjacent the first named pocket and inclosing the valved outlet, said second named pocket having apertures opening into the main water tank, and a coiled pipe in the first named pocket connecting with the tank at 10 the bottom and discharging into the second named pocket.

6. A water heating apparatus for use in conjunction with a bath tub comprising in combination with a tank adapted to be secured to the tub and having a valved discharge outlet opening thereinto, a fuel burner, a pocket or recess formed in the tank above the burner, a second pocket adjacent the first named pocket and inclosing the valved outlet, said second named pocket having apertures in the upper horizontal wall thereof and in the vertical wall at the bottom of the tank, and a coiled pipe in the first named pocket connected with the tank 25

at the bottom and discharging into the second named pocket.

7. A water heating apparatus for use in conjunction with a bath tub comprising in combination with a tank adapted to be secured to the tub and having a valved discharge opening leading thereinto, a plurality of fuel burners, the tank being provided with a pocket or recess above each burner, a pocket extending across the tank adjacent each of the burner pockets and inclosing the 30 outlet, and a pipe in each pocket connecting with the tank at the bottom and discharging into the pocket inclosing the outlet.

8. In combination with a water heating apparatus adapted to be secured to a bath tub and to discharge thereinto, of a pump supported by the apparatus, a fitting comprising a hollow body having an extension adapted to be secured to the waste opening of the tub, a second extension terminating in an upturned end arranged to receive the pump cylinder, and a closable opening at the bottom of the body for attaching a drainage fitting.

In testimony whereof, I sign this specification.

ROY J. BUELL.
